COIN CONTROLLED MECHANISM

Bertram C. Kenyon, Mishawaka, Ind., William W. Boa, Pittsburgh, Pa., and Clifford H. Green, Paris Township, Kent County, Mich., assignors to Grand Rapids Trust Company, Grand Rapids, Mich., a corporation of Michigan, receiver for Automatic Musical Instrument Company, a corporation of Delaware

Original application July 15, 1927, Serial No. 205,921. Divided and this application April 29, 1932, Serial No. 608,176

8 Claims. (Cl. 194—1)

The present invention relates to coin-controlled mechanisms, such as vending machines, automatic sound-reproducing instruments and the like; and its object is to provide improved means for operating or initiating the operation of such mechanisms, including an improved coin chute.

This and any other and more specific objects hereinafter appearing are attained by, and the invention finds preferable embodiment in, the illustrative structure and mechanism particularly described in the body of this specification and illustrated by the accompanying drawing, in which:

15 Figure 1 is an elevational side view of certain of the operative parts of a coin-controlled mechanism partially sectioned on line 1—1 of Figure 3, contained in a suitable casing one of whose walls is shown in vertical section;

20 Figure 2 is a like view of a portion thereof but showing the parts in another position; and

Figure 3 is a sectional view thereof taken on line 3—3 of Figure 1.

In the interior of a suitable casing 1 is mounted 25 the coin chute which comprises a fixed portion 2 and a portion 3 swingably mounted at 4 in one of the casing's vertical walls 5 and having a handle 6 and a coin-receiving slot 7 outside the casing. A coin 8 being inserted into this slot falls in the chute's portion 3 into held engagement with the bight 9 of a spring 10 surrounding chute portion 3 near its vent 11. As this chute portion is swung inwardly by its handle 6, the upper edge 12 of the coin in such movement striking the end 13 of a slot 14 in an arm member 15 swingably mounted at 16, (in which slot the coin has been held) swings said arm member upwardly to the position seen in Figure 2 and out of the locking engagement of its shoulder 40 17 with the inner side 18 of chute portion 3 immediately below the slot 19 through which said arm 15 slidably extends.

The chute portion 3 being thus unlocked and free to swing farther inwardly, the coin is carried thereby to a position wherein the cam edge 20 of the rib 21 of said arm member presses the coin downwardly by the sliding engagement of the arm member with the upper end 22 of slot 19, thus expanding or straightening spring 10 to 45 release its bight 9 from the coin, the arm member sliding in this movement of chute portion 3 in the lateral extensions 23 of chute portion 3.

The chute portion 3 having now reached the position indicated in dotted lines in Figure 1 and 50 its vent 11 being in registration with the upper

end 24 of the chute's fixed portion 2, the coin falls into and through this fixed portion and out of its vent 25 dropping on suitable means for operating the coin-controlled mechanism. Such means may be of various forms or types, a merely illustrative form or type thereof being shown as a lever fulcrumed at 26 on whose arm 27 the coin falls to operate it. The fixed portion 2 of the chute may in some cases be dispensed with.

In the normal position of the parts, the shoulder 17 holds chute portion 3 to a limited swinging movement. A spring 28 yieldingly holds chute portion 3 in the position shown in solid lines in Figure 1.

This application is divisional from our application, Serial No. 205,921, filed July 15, 1927.

The invention being intended to be pointed out in the claims, is not to be limited to or by details of construction of the particular embodiment thereof illustrated by the drawing or hereinbefore described.

We claim:

1. In a coin-controlled machine: a coin chute swingable to a position conveying a coin therein to the mechanism operated thereby, having 25 means for releasably retaining the coin; an element swingable by the swinging of the chute to its said position for releasing the coin from said retaining means, said element being swingable parallelly with the chute's swinging movement and 30 engaging the coin therein to release the same.

2. In a coin-controlled machine: a coin chute swingable to a position conveying a coin therein to the mechanism operated thereby, having means for releasably retaining the coin; an element 35 mounted extraneously of the chute and movable by said swinging of the chute to a position of said element wherein it engages the coin and releases the same from said retaining means.

3. In a coin-controlled machine: a coin chute swingable to a position conveying a coin therein to the mechanism operated thereby, having means for releasably retaining the coin; an element mounted extraneously of the chute and swingable by said swinging of the chute to a position of said element wherein it engages the coin and releases the same from said retaining means.

4. In a coin-controlled machine: a coin chute swingable to a position conveying a coin therein to the mechanism operated thereby, having means for releasably retaining the coin; an element mounted extraneously of the chute and having a cam, movable by said swinging of the chute to a position of said element wherein its cam en- 55

gages the coin and releases the same from said retaining means.

5. In a coin-controlled machine: a coin chute movable to a position conveying a coin therein to the mechanism operated thereby, having means for releasably retaining the coin; an element mounted extraneously of the chute and movable by said movement of the chute to a position of said element wherein it engages the coin and releases the same from said retaining means.

10. 6. In a coin-controlled machine: a coin chute movable to a position conveying a coin therein to the mechanism operated thereby, having a spring for releasably retaining the coin; an element movable by the movement of the chute to a position of said element wherein it engages the coin and expands the spring to release the same from the coin.

15. 7. In a coin-controlled machine: a coin chute swingable to an extreme position conveying a coin therein to the mechanism operated thereby, having means for releasably retaining the coin; means for holding the chute to a limited swung

position releasable by the engagement of the coin with said means in the limited movement of the chute, and for releasing the coin from said retaining means in the extreme position of the chute.

5. 8. In a coin-controlled machine: a coin chute swingable to an extreme position conveying a coin therein to the mechanism operated thereby, having a spring releasably retaining the coin; an element extending into the chute having a slot receiving the coin therein, a shoulder engaging the chute to hold the same to a limited movement and a cam engaging the coin and moving the same to expand the spring and release the same from the coin in the extreme position of the chute, said element being moveable by engagement of the coin therewith in said limited movement and movable by the movement of the chute to extreme position to cause the cam to engage and release the coin.
